UNITED STATES PATENT OFFICE.

WILLIAM WALKER, OF OTTAWA, ONTARIO, CANADA.

RAILWAY-TIE.

1,123,963.

Specification of Letters Patent.

Patented Jan. 5, 1915.

Application filed January 3, 1914. Serial No. 810,155.

To all whom it may concern:

Be it known that I, WILLIAM WALKER, a subject of the King of Great Britain, and resident of the city of Ottawa, Province of Ontario, Dominion of Canada, have invented 5 certain new and useful Improvements in Railway-Ties, and do hereby declare that the following is a full, clear, and exact description of the same, such as will enable 10 those skilled in the art to which it appertains to make and use the same.

My invention relates to reinforced concrete ties and particularly refers to that 15 type of tie utilized in railway practice, and the objects of the invention are to facilitate the securing of rails to such ties or their removal therefrom, to give a longer life to the ties, to dispense with the use of spikes and to generally overcome the objectionable 20 features associated with the use of wooden and other ties as found in use on railways, and it consists essentially of a reinforced concrete tie and chair particularly described in the following specification.

25 Figure 1 is a side elevation partly sectional of an improved form of tie. Fig. 2 is a side elevation partly sectional showing an alternate form of reinforcing tie. Fig. 3 is a plan view of Figs. 1 and 2. Fig. 4 30 is an end elevation partly sectional showing the reinforcing rods located in the tie.

Like letters of reference refer to like parts in the several drawings.

Referring to the drawings, A represents 35 the reinforced concrete tie which is substantially rectangular in cross section and provided with a chair 15 located in its upper face, the base of such chair extending partially through the said tie. The chair 15 40 may be of any suitable form and comprises an inner and an outer jaw 16 and 17, said inner jaw being provided with a recess 18 suitably formed at the base thereof and designed to engage with a flange or a bull- 45 head of the rail located between the said jaws. The base of the said chair consists of two downwardly projecting bars 19 extending transversely across the base of the said chair and being formed with wedge shaped 50 recesses located around the outer edges thereof, such recesses being designed to engage with the concrete of the tie and form an anchoring means for the said chair. The 55 said bars 19 are further provided with ori- fices 20 extending therethrough, such ori- fices being adapted to engage with reinforc-

ing rods 21 located in the said tie and extending longitudinally therein, such reinforcing rods forming a further anchoring means for the said bar and preventing such 60 chair from becoming loose, due to vibration or any other cause.

In Fig. 2 the upper reinforcing rod is shown slightly bent and this form of rod is designed to prevent any movement of the 65 chair which might otherwise occur when a straight rod is used, such as is shown in Fig. 1. It will, however, be understood that although two forms of reinforcing rods adapted to hold the chair 15 in position are 70 here shown that the special features and shape of the rod can only be determined by experimental use of such a tie, so that such forms must not be taken as altogether binding, but adapted to be altered as the applicant finds desirable. Further, the outer jaw of the chair 15 is provided with a strengthening rib 22 and should it be found desirable it will be understood that a similar strengthening rib could be added to the 75 inner jaw of the said chair. The location of the reinforcing rods is likewise a matter which can only be determined with great difficulty, but in the illustrations here submitted they are shown with the lower rods 80 farther separated apart than the upper rods, thereby distributing the stress more evenly 85 throughout the reinforced concrete tie.

The formation of the jaws adapted to engage with the key or wedge piece 23 is suit- 90 ably formed and may be either substantially right angular to the top face of the tie A or formed with grooves.

Having described my invention I will 95 now show the manner in which it is used.

The tie is placed on the bed prepared for it, and well packed with rubble and the like. When a desired number of ties have been arranged in their proper relative positions the rail B is located between the jaws 16 and 100 17 of the chair 15, the flange or bullhead of the rail engaging with the recess 18, the rail being secured in position by means of the wedge 23 located between the web of the 105 said rail B and the inner face of the outer gripping jaw 17, such wedge when driven in securing the rail B firmly in position. Any undue strain of vibration caused by the rolling stock passing over such a tie A is taken up by the reinforcing rods 21 located in the 110 said tie and any tendency of the chair 15 becoming loose, due to such vibration, is

overcome by means of the edges 19 being embedded in the concrete of the tie.

As many changes could be made in the above construction and many apparently widely different embodiments of my invention, within the scope of the claims, constructed without departing from the spirit or scope thereof, it is intended that all matter contained in the accompanying specification and drawings shall be interpreted as illustrative and not in a limiting sense.

What I claim as my invention is:

1. A reinforced concrete railway tie comprising a base, a chair located on the upper face thereof, the base of the said chair being provided with bars extending transversely across the bottom thereof, such bars being designed to be located in the base of the said tie and having orifices extending

therethrough, and reinforcing rods extending longitudinally of the said tie and designed to engage with the said orifices located in such bars, as and for the purpose specified. 20

2. A reinforced concrete railway tie comprising a base, a chair having bars extending transversely across the bottom face thereof, such bars being provided with wedge shaped recesses on the outer edges, and means of securing a rail to the said chair, as and for the purpose specified. 25 30

In witness whereof I have hereunto set my hand in the presence of two witnesses.

WILLIAM WALKER.

Witnesses:

P. M. GARROW,
M. MAHONEY.
